UNITED STATES PATENT OFFICE.

WAWRZENIEC GOLYMBIEWSKI, OF CHICAGO, ILLINOIS.

WINDOW-OPERATING MECHANISM.

Application filed May 11, 1922. Serial No. 560,054.

To all whom it may concern:

Be it known that I, WAWRZENIEC GOLYMBIEWSKI, a citizen of the United States of America, residing at Chicago, in the county 5 of Cook and State of Illinois, have invented certain new and useful Improvements in Window-Operating Mechanisms, of which the following is a specification.

This invention relates to certain new and 10 useful improvements in the construction of windows and operating mechanism therefor and embodies in a window sash of the sliding type, a hinged section supporting the window pane, capable of being swung to 15 a position inwardly of the window frame for purposes of cleaning the panes.

The invention further embodies improvements in operating mechanism for vertically sliding the sashes and includes a particular 20 cord arrangement associated with the sashes and devices for operating the cords to raise and lower the window sashes.

A further object of the invention has reference to a sash that is bodily removable 25 from a window frame and the same being retained in operative position within the frame by spring devices carried by the frame and engageable with the removable sash.

With the above general objects in view 30 and others that will appear as the nature of the invention is better understood, the same consists in the novel construction, combination and arrangement of parts hereinafter 35 more fully described, illustrated in the accompanying drawings, and pointed out in the appended claims.

In the drawings forming a part of this application and in which like designating 40 characters refer to corresponding parts throughout the several views:—

Figure 1 is a front elevational view partly in section, of the improved window frame and sash having the operating cords associated with the upper and lower sashes for 45 raising and lowering the same.

Figure 2 is a vertical sectional view taken on line 2—2 of Figure 1 showing the arms positioned beneath the window sill and associated with the operating cords for shifting the sashes.

Figure 3 is a vertical sectional view taken on line 3—3 of Figure 1 showing the sections of the operating cord and the guide 50 pulleys therefor.

Figure 4 is a horizontal sectional view

taken on line 4—4 of Figure 1, showing the connections between the lower sections of the operating cords and the arms associated with the operating cords for raising and 60 lowering the upper and lower sashes,

Figure 5 is a horizontal sectional view taken on line 5—5 of Figure 1, showing by dotted lines the hinged section of one of the sashes partially opened and the spring device 65 for retaining the sash frame in the window frame,

Figure 6 is a fragmentary side elevational view of the upper and lower sashes showing the edge grooves for the operating cords, 70

Figure 7 is a detail sectional view taken on line 7—7 of Figure 1 showing the operating handles for the upper and lower sliding sashes,

Figure 8 is a detail sectional view taken 75 on line 8—8 of Figure 5 showing the spring device carried by the window frame in engagement with the sash frame,

Figure 9 is a detail sectional view showing in end elevation, the sash frame retaining device.

Figure 10 is a fragmentary detail sectional view of a portion of the window sash showing the connection between one of the operating cords and the sash, 85

Figure 11 is a fragmentary perspective view of the window sill showing the bottom face thereof, the operating cord guide pulleys and the rod that slidably supports the cord shifting arm, and 90

Figure 12 is a diagrammatic perspective view of the operating cord arrangement for the upper and lower sashes.

Referring more in detail to the accompanying drawings, a sash frame supporting 95 vertically sliding sashes is removably mounted within a window frame 1 as shown in Figures 1 and 5 the sash frame embodying hollow side bars 2, an upper bar 3, and a lower sill 4. The means for retaining the 100 sash frame in position in the window frame 1 includes a spring device shown more clearly in Figures 5, 8 and 9, a spring strip 5 being secured to the face of one side wall of the window frame and carrying upon the 105 free end thereof a T-shaped head 6 that is received in a channel iron 7 secured in a cut-out portion provided in the adjacent side bar of the sash frame, the spring device 5 securely retaining the sash frame within the 110 window frame opening. The opposed side faces of the sash frame 2 are provided with

the usual parting strips for upper and lower sliding sashes 8 and 9 respectively, each sash embodying a sliding frame 10 and a hinged section 11 supporting a pane of glass, the 5 hinged sections 11 swinging upon a vertical axis to a position inwardly of the window frame to permit access to the pane for cleaning purposes or otherwise. The usual button lock 12 is carried by the upper and lower 10 sashes for retaining the same in locked position.

The upper and lower sashes 8 and 9 are vertically slidable in the sash frame and have associated therewith a series of pulleys 15 and cords that are operated by handle arms disposed beneath the sills 4 as illustrated. The side bars 2 of the removable sash frame are of hollow construction and have rotatably supported midway thereof a pair of 20 pulleys diagrammatically shown in Figure 12, one pair of pulleys being designated by the reference numerals 13 and 14, while the other pair of pulleys journaled in the opposite side bar 2 is designated by the reference numerals 15 and 16. Each side bar 2 as shown in Figure 1, is cutaway midway the upper and lower ends thereof to accommodate the rotatable mounting of pairs of pulleys designated by the reference numerals 25 17—18 and 19—20. As shown in Figure 11, a depending U-shaped frame or bracket 21 is carried by the lower side of the sill 4, one of the brackets having journaled therein four pulleys indicated by the reference numerals 13^a, 14^a, 17^a, and 18^a. The other bracket 21 has four pulleys journaled therein designated by the numerals 15^a, 16^a, 19^a, and 20^a. The operating cords passing over the several pulleys are associated with the 30 handle arms 22 and 23, the arm 22 being slidable upon the guide rods 24 while the handle arm 23 is slidable upon guide rods 25 arranged parallel to each other and depending from the sill 4 as clearly shown 35 in Figure 11.

The operating cords passing over the pulleys positioned midway the upper and lower ends of the side bars 2 extend into grooves 26 provided in the opposite vertical side edges of the sashes as shown in Figures 5, 6 and 10, one end of the cord being knotted as at 27 and anchored to the sash by the removable strips 28. The pulleys 14—18, 14^a—18^a, 16—20, and 16^a—20^a are associated 40 with the lower sash 9, while the remaining pairs of pulleys are associated with the upper sash 8. The operating cords connected to the lower sash 9 and passing over the pulleys, are connected to the handle arm 23, the tracing of the cords being clearly discernible from an inspection of Figure 12. The cord 30 is anchored as at 29 adjacent the lower edge of the right hand side strip of the lower sash 9, passing upwardly 45 through the groove 26 in the edge of the

strip and over the pulley 20, thence downwardly beneath the pulley 20^a and is secured to the arm 23. The corresponding cord 31 anchored adjacent the lower end of the opposite side of the lower sash as at 32 70 passing upwardly over the pulley 18, thence downwardly and around the pulley 18^a, extending entirely across the space beneath the sill 4 for passage over the pulley 20^a and then retraced to be secured to the arm 23. 75 An operating cord 33 is anchored as at 34 adjacent the upper edge of the right hand side of the lower sash, the cord passing beneath the pulley 20 and upwardly and over the pulley 16 and downwardly beneath the pulley 16^a to extend across the space beneath the sill 4 for passage over the pulley 14^a, and then reversely directed to be secured to the handle arm 23. The operating cord 35 is anchored as at 36 to the upper left hand side of the lower sash, passing beneath the pulley 18, upwardly and over the pulley 14 and then downwardly beneath the pulley 14^a to be secured to the arm 23. The operating cords associated with the upper sash 8 90 are connected thereto in a like manner, the cord 37 being anchored as at 38 to the lower right hand edge of the upper sash passing over the pulley 19, and downwardly around the pulley 19^a to be secured to the handle 95 arm 22 normally occupying a position adjacent the left hand side of the window. The companion cord 39 positioned at the opposite side of the upper sash is anchored to the lower left hand side thereof as at 40, the same 100 passing over the pulley 17, thence downwardly around the pulley 17^a across the space beneath the sill 4 around the pulley 19^a and thence directed backwardly to be secured to the arm 22. The cord 41 is anchored as at 42 to the upper right hand edge of the upper sash passes downwardly beneath the pulley 19 and upwardly over the pulley 15 directly downwardly beneath the pulley 15^a to traverse the pulley 13 and 110 reversely directed to be secured to the arm 22. The corresponding cord 43 at the opposite side of the sash is anchored to the upper left hand edge thereof as at 44 and passes downwardly beneath the pulley 17, upwardly and over the pulley 13, thence 115 downwardly beneath the pulley 13^a and directly secured to the handle arm 22. The operation of the device will be readily understood from an inspection of Figure 12 120 of the drawing, assuming that it is desired to raise the lower sash 9, the handle arm 23 is shifted upon the guide rods 25 moving the cords attached thereto and to the lower sash, the cord 30 being drawn over 125 the pulleys 20 and 20^a by the arm 23 while the cord 31 is run over the pulleys 18, 18^a and 20^a simultaneously with this movement, the cords 33 and 35 attached as at 34 and 36 respectively to the upper edges of the 130

- lower sash are shifted over the pulleys associated therewith by movement of said arm. When the lower sash 9 is in an elevated position and is to be lowered, the strain is placed upon the cords 33 and 35 while the entire reverse movement of the several cords is effected. The cords attached to the lower ends of the sash being employed for elevating the same, while the cords attached to the upper end of the sash are intended for lowering the same. The cords connected to the upper sash 8 work in a similar manner, except that the cords 41 and 43 attached to the upper end of the upper sash effect a lowering movement thereof when the handle arm 22 is operated, while the cords 37 and 39 attached to the lower edge of the upper sash effect the raising movement thereof when the handle arm 22 is shifted.
- 20 While the form of the invention herein shown and described is what is believed to be the preferred embodiment thereof, it is nevertheless to be understood that various forms, modifications and arrangements of 25 the parts may be made without departing from the spirit and scope of the invention as claimed.
- Having thus described the invention, what I claim as new is:—
- 30 1. An operating mechanism for a window comprising in combination with sliding sashes, a series of pulleys journaled adjacent the lower corner edges of the sash frame, a series of pulleys journaled at each 35 side of the sliding sashes adjacent the meeting line, handle arms slidably mounted transversely beneath the lower sash and sets of operating cords separately connected to the sashes and to said handle arms whereby 40 sliding movement of either of the handle arms will raise or lower the desired sash.
2. An operating mechanism for a window comprising in combination with sliding
- sashes, two sets of pulleys journaled adjacent the opposite meeting edges of the 45 sashes, four aligned pulleys journaled adjacent each lower edge of the window sill, guide rods depending from the window sill, a pair of handle arms slidable on said rods, and two sets of cords passing over said pulleys and secured to the sashes and handle arms in a manner whereby shifting movement of the handle arms effect raising and lowering movements of the window sashes.
3. Operating mechanism for windows 55 comprising in combination with sliding sashes, sets of pulleys journaled adjacent the opposite meeting edges of the sashes, and adjacent each lower edge of the window sill, handle arms slidably mounted transversely beneath the window sill, sets of operating cords passing over the pulleys and each set having the ends of the cords secured to the upper and lower side edges of the sash and connected to one of the handle arms 65 whereby movement of the handle arm will shift the set of cords to effect raising and lowering movements of the sash.
4. Operating mechanism for windows 70 comprising in combination with sliding sashes, sets of pulleys journaled adjacent the opposite meeting edges of the sashes, and adjacent each lower edge of the window sill, handle arms slidably mounted transversely beneath the window sill, sets of operating 75 cords passing over the pulleys and each set having the ends of the cords secured to the upper and lower side edges of the sash and connected to one of the handle arms and lying in grooves in the side edges of the 80 sash whereby movement of the handle arm will shift the desired set of cords to effect raising and lowering movements of the sash.

In testimony whereof I affix my signature.

WAWRZENIEC GOLYMBLEWSKI.
